CLAIM

The ornamental design for a water purifier, as shown and described.

DESCRIPTION

FIG. 1 is a front, right side, perspective view of a water purifier showing our new design in a first state before operation of the water purifier;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, right side, perspective view of the water purifier showing our new design in a second state where the water outlet is rotated to the right;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a front, right side, perspective view of the water purifier showing our new design in a third state where the water outlet is extended down after the water outlet is rotated to the right;

FIG. 16 is a front view thereof;

FIG. 17 is a rear view thereof;

FIG. 18 is a left side view thereof;

FIG. 19 is a right side view thereof;

FIG. 20 is a top view thereof; and,

FIG. 21 is a bottom view thereof.

The broken lines indicate unclaimed portion of the article that form no part of the claimed design.
